(57) **CLAIM**

The ornamental design for an audio equipment, as shown and described.

DESCRIPTION

FIG. 1 is a top plan view of an audio equipment showing our new design;

FIG. 2 is a front elevation view thereof;

FIG. 3 is a rear elevation view thereof;

FIG. 4 is a left side elevation view thereof; the right side elevation view is a mirror image thereto;

FIG. 5 is a rear, right, top perspective view thereof;

FIG. 6 is a front, right, top perspective view thereof; and,

FIG. 7 is a bottom plan view thereof.

The broken line in the figure drawings represents unclaimed environment only and forms no part of the claimed design.
